(57) **CLAIM**

The ornamental design for a housing for electrical or cabling wires, as shown and described.

DESCRIPTION

FIG. 1 is a front isometric view of a housing for electrical or cabling wires, showing my new design;

FIG. 2 is a front view thereof;

FIG. 3 is a back view thereof;

FIG. 4 is a right side view thereof;

FIG. 5 is a left side view thereof; and,

FIG. 6 is a top plan view thereof.

The housing for electrical or cabling wires is shown with a symbolic break in its length. The appearance of any portion of the article between the break lines forms no part of the claimed design.
